SAFETY-RAZOR HANDLE

Louis Vincent Nigro, Chelsea, Mass.

Application November 1, 1955, Serial No. 38,683

Term of patent 14 years

(Cl. D22—3)

Fig. 1

Fig. 2

Fig. 3

Fig. 1 is a perspective view, on an enlarged scale, of a safety-razor handle embodying my design;

Fig. 2 is a fragmentary, side elevational view of the lower portion thereof; and

Fig. 3 is a bottom plan view thereof.

The side of the handle opposite to that shown in Fig. 1 presents a substantially similar appearance; the numerals and gauge markings shown near the top of Fig. 1 continue all the way around the handle.

I claim:

The ornamental design for a safety-razor handle, substantially as shown and described.
